TURBINE STATOR ASSEMBLY

Donald G. Zimmerman, Indianapolis, Ind., assignor to General Motors Corporation, Detroit, Mich., a corporation of Delaware

Application November 1, 1952, Serial No. 318,177

7 Claims. (Cl. 253—78)

This invention relates to elastic fluid turbines for high temperature fluids and more particularly to a means for supporting the stator vane assemblies of an axial flow turbine in the external casing of the turbine.

A known type of multistage axial flow gas turbine includes a plurality of external casing rings that are bolted together and a plurality of stator vane assemblies located within the external casing and peripherally flanged thereto for support. The stator vane assemblies tend to expand more than the external casing so they are segmented along planes extending generally in an axial direction. Clearance is provided between the segments so that they may expand peripherally without deforming the external casing and yet maintain the desired minimum clearance between the turbine rotor and the stator vane assemblies. The stator vane assemblies have been located by radial dowels that threaded through the external casing and extended into annular bosses on the segments prior to this invention.

The object of the invention is to provide an improved turbine casing construction including an improved means for locating the stator vane assemblies in the external casing.

Further objects and advantages of the present invention will be apparent from the following description, reference being had to the accompanying drawings wherein a preferred form of the invention is clearly shown.

In the drawings:

Fig. 1 is a longitudinal section of a portion of a multi-stage axial flow turbine constructed in accordance with the invention;

Fig. 2 is an enlarged partial section illustrating the joint locating of the first and second stator vane assemblies to the external casing by a common key;

Fig. 3 is an enlarged partial section illustrating the joint locating of the third and fourth stator vane assemblies to the external casing by a common key;

Fig. 4 is an enlarged partial section illustrating the interflanged interconnection between the first and second stator vane assemblies and the external casing;

Fig. 5 is an enlarged section illustrating the interflanged interconnection between the third and fourth stator vane assemblies and the external casing;

Fig. 6 is a perspective elevation of a first and second stator vane locating key;

Fig. 7 is a perspective elevation of a third and fourth stator vane locating key;

Fig. 8 is a partial plan view of the turbine casing having portions of the external casing members partially broken away to illustrate the segmented nature of the stator vane assemblies and their keying arrangement; and

Fig. 9 is a partial elevation view of the first stage stator ring taken along the plane indicated by the line 9—9 of Fig. 8.

Referring now to the drawings in detail, the turbine assembly comprises two major components, a turbine rotor assembly and a turbine casing assembly. The turbine casing assembly includes an outer casing structure

that encircles the blade system of the turbine and an inner casing structure supported thereby and defining therewith the inlet and exhaust portions of the turbine and providing bearing support for the turbine rotor assembly. The outer casing structure includes a rigid multipart external casing structure and a segmented, relatively flexible, stator-vaned internal casing structure secured thereto. The turbine rotor assembly includes a bladed drum built up from alternating bladed disks and nonbladed spacer disks. The forenoted turbine construction may be conventional and therefore only so much of the structure as is necessary to enable one skilled in the art to understand the invention is illustrated. The invention is illustrated as applied to a four-stage turbine, but it should be realized that it may be applied to as many stages as may be desired.

A rear casing 10, an intermediate casing 12 and a forward casing 14 which comprise the primary structural components of the turbine casing assembly are bolted together at 16 and 18, the rear casing 10 supporting an exhaust casing structure 20 by bolts 22. The exhaust casing structure 20 includes outer shells 24 and 26 and inner cones 28 and 30, the inner cones and the rear turbine bearing being supported from the rear casing 10 by radial struts (not shown). The inlet casing structure 32 includes the forward casing 14 and an inner casing 34 and a forward bearing support plate 36 supported therefrom by radial struts (not shown). The turbine rotor assembly 38 includes blade disks 40 and spacer disks 42 suitably secured together for rotation in the turbine casing in the usual manner. The outer casing structure includes four stator vane assemblies supported from the casings 10, 12 and 14 by peripheral tongue and groove structure to be described.

35 The stator vane assemblies form the fixed blading for the turbine and an internal casing structure for the turbine casing assembly. The stator vane assemblies include the outer shroud rings 70, 76, 82 and 88 and the inner shroud rings 52 secured thereto by the stator vanes 54, the first stage inner shroud ring being additionally supported by the inner casing 34 and the remaining inner shroud rings serving as gas seals between the blading stages of the turbine rotor.

The turbine unit is assembled from rear to front as will be described. The external casings 10, 12 and 14 are formed with peripheral tongues 60, 62, 64 and 66 that extend axially to support the stator vane assemblies. The fourth stage outer shroud ring 70 is formed with a peripheral grooved flange 72 that embraces the tongue 62 and a peripheral flange 74 received in the groove formed by the tongue 60. The third stage outer shroud ring 76 is formed with a peripheral tongue 78 received in the groove of the flange 72 and a peripheral flange 80 received in the groove formed by the tongue 64. The first stage outer shroud ring 82 is formed with a peripherally grooved flange 84 that embraces the tongue 66 and a peripheral ridge 86 that bears against the interior of the forward casing 14. The second stage outer shroud ring 88 is formed with a peripheral tongue 90 received in the groove of the flange 84 and a peripheral flange 92 received in the groove formed by the tongue 64.

As considerable temperature differential exists between the shroud ring assemblies and the external casings 10, 12 and 14 during turbine operation. The temperature differential tends to cause deformation of either or both the stator vane assemblies and external casings so the stator vane assemblies are segmented along planes extending generally longitudinally of the turbine axis, and clearance spaces 94 (Figs. 8 and 9) are provided between the segments so that they may expand peripherally rather than radially (the outer shroud rings being relatively flexible with respect to the casings 10, 12 and 14). The tongue

and groove structure interconnects the external casings and the outer shroud rings and constrains the stator vane assemblies radially so that they remain properly centered at all times. The individual segments of the stator vane assemblies are located circumferentially and maintained in their proper circumferential location by keys 96 and 98.

In the construction illustrated, each stator vane stage includes six stator vane segments. The adjacent segments of the third and fourth stages are located by six keys 96 and the adjacent segments of the first and second stages are located by six keys 98. Each key is connected to its pair of adjacent segments at the middle of the segments so that the segments are free to expand peripherally from their center. The clearance spaces 94 accommodate such expansion. It should be understood that the degree of segmentation of stator vane assemblies may be varied if desired. The torque reaction from the stator vane assemblies is transferred to the casings 10, 12 and 14 by the keys 96 and 98. The tongue and groove interconnections are slotted as shown in Figs. 2 and 3 in an axial direction to receive the keys, and it should be noted that the keys are located wholly within the outer casing structure, i. e., they do not extend outside the casings 10, 12 and 14 nor inside the outer shroud rings 70, 76, 82 and 88. Each key 98 is received in aligned complementary slots that traverse the casing tongue 66, the first stage shroud ring flange 84 and the second stage shroud ring tongue 90. Each key 96 is received in aligned complementary slots that traverse the casing tongue 62, the third stage shroud ring tongue 78 and the fourth stage shroud ring flange 72.

The assembly of the turbine unit is accomplished as follows: The exhaust casing structure 20 is mounted vertically in a suitable fixture. The rear casing 10 is then bolted to the exhaust casing structure 20. The turbine rotor assembly is next lowered by an overhead hoist into the forward portion of the rear casing 10. The fourth stage stator segments are then placed in position and the turbine rotor assembly is lowered further into the rear casing 10. The second stage stator segments are then inserted between the first and second blading stages of the rotor and the third stage stator segments are inserted between the second and third blading stages of the rotor; and the turbine rotor, with stator segments in place, is lowered into its final location in the rear casing 10 so that the flange 74 engages the tongue 60. The keys 96 are then inserted in the slotted tongue and groove interconnections of the third and fourth stages so that these stages are keyed together. The intermediate casing 12 is then slipped over the second and third stage stator segments so that the tongues 62 and 64 engage the flanges 72 and 92 respectively, the slots in the tongue 62 engaging the keys 96 to key the third and fourth stage stator segments to the intermediate casing 12. The intermediate casing 12 is then bolted to the rear casing 10. The keys 98 are next inserted in the slots in the tongues 66 and 90 and the inlet casing structure 32, with its first stage stator segments in place, is then slipped into position with the grooved flange 84 engaging the tongues 66 and 90 and the keys 98 being received in the slots in the grooved flange. The inlet casing structure 32 is then bolted to the intermediate casing 12 to form the complete turbine unit.

Advantages attained by utilizing the keying arrangement of the invention in preference to the usual radial dowels are the elimination of bores through the casing for mounting the dowels and the subsequent possibility of motive fluid leakage therethrough, the elimination of dowel receiving bosses on the segments, easier assembling of the turbine, and a reduction in the number of segment locators required, i. e., one key serves to locate two segments whereas two dowels were previously required.

While the preferred embodiment of the invention has been described fully in order to explain the principles of

the invention, it is to be understood that modifications in structure may be made by the exercise of skill in the art within the scope of the invention, which is not to be regarded as limited by the detailed description of the preferred embodiment.

I claim:

1. An elastic fluid turbine comprising an annular casing, a stator vane shroud ring disposed in said casing, peripherally extending tongue and groove structure on said casing and said ring for mounting said ring in said casing, a plurality of peripherally spaced slots each traversing said tongue and groove structure, and keys located in said slots of said tongue and groove structure for circumferentially locating said ring in said casing.
2. A multistage elastic fluid turbine comprising an annular casing, a pair of stator vane shroud rings disposed in said casing in abutting end to end relation, peripherally extending tongue and groove structure on said casing and the abutting ends of said rings for mounting said rings in said casing, a plurality of peripherally spaced slots each traversing said tongue and groove structure, and keys wholly disposed within said casing located in said slot of said tongue and groove structure for circumferentially locating said rings in said casing.
3. A multistage elastic fluid turbine comprising an annular casing, a pair of stator vane shroud rings disposed in said casing in abutting end to end relation, means for mounting said rings in said casing comprising a peripheral tongue formed on said casing and a peripheral tongue formed on the abutting end of one of said rings cojointly received in a peripheral groove formed in the abutting end of the other of said rings, a plurality of peripherally spaced slots each traversing said tongues and said groove, and keys located in said slots of said tongues and said groove for circumferentially locating said rings in said casing.
4. A multistage elastic fluid turbine comprising an annular casing, a pair of stator vane shroud rings disposed in said casing in abutting end to end relation, means for mounting said rings in said casing comprising a peripheral tongue formed on said casing and a peripheral tongue formed on the abutting end of one of said rings cojointly received in a peripheral groove formed in the abutting end of the other of said rings, a plurality of peripherally spaced slots each traversing said tongues and said groove, and keys located in said slots of said tongues and said groove for circumferentially locating said rings in said casing, said keys being wholly disposed within said casing.
5. A multistage elastic fluid turbine comprising an annular casing, a pair of annular members disposed in said casing in abutting end to end relation, each of said members being parted substantially longitudinally of the turbine to provide a plurality of arcuate stator vane supporting segments, the abutting ends of said members being peripherally joined to each other and to said casing by a tongue and groove connection to support said members in said casing, a plurality of peripherally spaced slots each traversing said connection, and keys located in said slots of said connection for circumferentially locating each of said segments in said casing.
6. A multistage elastic fluid turbine comprising an annular casing, a plurality of arcuate stator vane supporting elements disposed circumferentially in said casing to form a pair of stator vane shroud rings, said rings being disposed in said casing in abutting end to end relation, means for mounting said rings in said casing comprising a peripheral tongue formed on said casing and a peripheral tongue formed on the abutting end of one of said rings cojointly received in a peripheral groove formed in the abutting end of the other of said rings, a plurality of peripherally spaced slots each traversing said tongues and said groove, and a plurality of keys located in said slots of said tongues and groove for circumferentially locating said rings in said casing, each of said keys interconnecting a pair of said elements.

7. A multistage elastic fluid turbine comprising first and second annular members having abutting ends secured together to form an external casing for the blade system of the turbine, said first member having an internal flange on its abutting end that underlies the inner surface of the abutting end of said second member in radially spaced relation, a set of first arcuate stator vane supporting elements disposed circumferentially in said first member, a set of second arcuate stator vane supporting elements disposed circumferentially in said second member, said first and second elements being in abutting end to end relation, said second elements having their abutting ends grooved to receive said flange and the abutting ends of said first elements for mounting said elements in said

casing, said flange and said abutting ends of said elements having a plurality of peripherally spaced transverse slots, and a plurality of keys each disposed in one of said slots for circumferentially locating said elements in said casing.
